TELEVISION LAMP

William N. de Sherbinin, Brookfield, Conn.

Application March 16, 1951, Serial No. 14,522

Term of patent 14 years

(Cl. D48—20)

To all whom it may concern:

Be it known that I, William N. de Sherbinin, a citizen of the United States of America, residing in Brookfield, Fairfield county, Connecticut, have invented a new, original, and ornamental Design for Television Lamp, of which the following is a specification, reference being had to the accompanying drawing, forming a part thereof:

In the drawing:

Fig. 1 is a perspective view of a television lamp embodying my new design.

Fig. 2 is a top plan view of the lamp;

Fig. 3 is a side elevation of the lamp, and

Fig. 4 is a front elevation of the lamp.

The dominant features of my design are shown in solid lines in the drawing.

I claim:

The ornamental design for a television lamp, substantially as shown and described.

WILLIAM N. DE SHERBININ.
